UNITED STATES PATENT OFFICE.

FRANK E. CASE, OF SCHENECTADY, NEW YORK, ASSIGNOR TO GENERAL ELECTRIC COMPANY, A CORPORATION OF NEW YORK.

TROLLEY-CONTROLLING APPARATUS.

No. 830,568.

Specification of Letters Patent.

Patented Sept. 11, 1906.

Application filed March 10, 1905. Serial No. 249,376.

To all whom it may concern:

Be it known that I, FRANK E. CASE, a citizen of the United States, residing at Schenectady, county of Schenectady, State of New York, have invented certain new and useful Improvements in Trolley-Controlling Apparatus, of which the following is a specification.

The present invention relates to electric railways, and more particularly to apparatus arranged on a car or locomotive for collecting current from a trolley-wire or third rail. It is sometimes found advisable or necessary to operate one portion of a railway by means of current supplied by a third rail arranged near the road-bed and another portion by means of current carried by an overhead conductor or trolley-wire. It is customary to arrange the current-collecting devices so that one or both may be retracted when not employed in collecting currents.

In one aspect the present invention relates to means for automatically retracting a current-collecting device when the car or train approaches a point at which the collecting device is no longer in service, all the parts of the apparatus returning to their normal inoperative positions.

In another aspect the present invention may be considered as consisting of a pneumatically-controlled current-collecting device which is automatically retracted when the car or train reaches a predetermined point on the track.

In another aspect the present invention relates to a novel form of valve mechanism applicable particularly to pneumatic trolley apparatus.

To the above ends I have associated with a pneumatically-controlled current-collecting device a motorman's valve arranged to alternately connect the immediate controlling means for the collecting device to atmosphere and to a suitable source of compressed air. The valve is moved from its normal position, in which it exhausts the air from the controlling mechanism against the tension of a spring and is locked in its operative position by means of a suitable catch. This catch is so arranged that it assumes its retracted position whenever the pressure within the main valve is less than that required to cause the

collecting device to be moved to its operative position. Therefore as long as no air is being supplied to the valve it will always return to its normal or "off" position unless manually held in its working position. At the point at which it is desired to retract the current-collecting device there is arranged in proximity to the roadway a stop which operates to open a small valve upon the car, and thereby exhaust the air from the catch-controlling device. The catch is thereupon retracted so as to permit the main valve to be returned to its off position by means of its spring. Upon reaching its off position the main valve exhausts the air from the controlling mechanism for the current-collecting device, and the current-collecting device is retracted. By this arrangement the motorman's valve is left in its normal position, so that in order to again operate the current-collecting device the valve is simply turned from its off to its running position.

The present invention will be more clearly understood and further objects thereof will be apparent from the following description thereof.

A preferred form of the present invention is illustrated in the accompanying drawings, in which—

Figure 1 shows a single car equipment and the stop for automatically retracting the trolley. Fig. 2 shows in cross-section the pilot-valve mechanism which is controlled by the fixed stop. Fig. 3 is a vertical cross-section of the motorman's valve. Fig. 4 is a plan view of that portion of the valve-casing containing the several ports, and Fig. 5 is a plan view of the movable member of the motorman's valve.

Similar reference characters will be used throughout the specification and drawings to indicate corresponding parts.

Reference being had to Fig. 1, T is the current-collecting device, represented as one which is adapted to be mounted upon the roof of a car or locomotive in order to make contact with an overhead conductor or trolley-wire. X, M, M' are two motorman's valves, preferably arranged at opposite ends of the car or locomotive and adjacent the electric controllers C, C'. A is an air-compressor supplying air to a suitable reservoir.

R. The reservoir R is connected to each of the valves M and M' by means of a pipe 1 and a branch pipe 1^a, and the valves are in turn connected to the trolley mechanism by means of a pipe 2 and branch pipe 2^a.

The current-collecting device and its immediate operating and controlling mechanism may be of any preferred or desired type; but I have illustrated a construction set forth in an application filed by Samuel B. Stewart, Jr., for underrunning-current collector, filed November 23, 1904, Serial No. 233,956. This mechanism, which in itself forms no part of the present invention, consists briefly of a shell t, near the upper end of which are pivotally secured, as at 4 4, a pair of levers or sets of levers 5 5, to the outer end of each of which is pivotally secured, as at 7, a lever 8. The several levers 8 carry at their upper ends the contact-shoe 11, the lower ends of the levers being connected, respectively, with the levers 5, near the fulcrums 4 of the latter levers, by means of the springs 13. It is evident that when otherwise free the springs 13 draw the levers 7 and the levers 8 toward each other and cause the collector-shoe 11 to rise. The collector-shoe is normally held retracted, however, by means of a T-head 24, carried at the upper end of a rod 25 and adapted when moved downward to engage near the ends of its arms with pieces 26, extending from the levers 5. The rod 25 is normally forced downwardly by a heavy compression-spring 29, bearing at one end against the upper end of the cylinder 30 and at its other end against a piston 31, secured to the lower end of the rod 25. When air is admitted from the pipe 2^a to the cylinder 30, the piston 31 is forced upwardly, disengaging the arms of the member 24 from the members 26 and permitting the springs 13 to raise the collector-shoe. When either of the valves M is operated to admit air to the collector-shoe mechanism, the valve is maintained in its operative position against the tension of a spring by means of a pneumatically-actuated catch which will be hereinafter described. A pipe 3 communicates with the catch-actuating mechanism of each of the valves M M', and by exhausting pressure from this pipe when one of the valves is in its operative position the catch is retracted and the spring in the valve throws the valve to its off position, exhausting the air from the cylinder 31 and causing the spring 29 to force the collector-shoe 11 downwardly. A branch 3^a to pipe 3 leads to the pilot-valve mechanism 32, supported on a bracket 33, which is secured to the car in such a position that an oscillating member 34, pivotally secured to the bracket at 35 may ride up on a short section of rail 36, which may be separate from the third rail and is preferably arranged adjacent the track.

The pilot-valve mechanism is shown in Fig. 2. The valve proper consists of a casing

37, into which the pipe 3^a opens. The casing 37 is provided with an opening 38, connecting the interior of the casing with the atmosphere. Normally this opening is closed by means of a spring-pressed valve 39, which bears against a seat 40 in the interior of the casing and shuts off the interior of the casing from the opening 38. The oscillating shoe is provided with an upwardly-projecting arm 41, which is preferably yieldingly pivoted thercon, as at 42, and held in its normal position by means of a spring 43. The arm 41 carries near its upper end a roller 44, which is adapted to engage with a head 45, arranged upon the projecting stem of the valve 39. Normally the shoe 34 is depressed by means of the spring 46 until the shoulder 47 upon the shoe comes into contact with the bracket 33. In this position of the shoe the roller 44 is held out of engagement with head 45, and consequently the valve 39 remains seated. When, however, the shoe 34 rides up on the rail 36, a sufficient oscillation of the shoe is produced to force the roller 44 against the head 45 on the valve-stem and unseat the valve, as shown in Fig. 2. As soon as the shoe 34 passes from the rail 36 it is again forced downwardly through the action of the spring 46 and the valve 39 again seats itself, so that when the motorman's valve is again turned to its working position there is no communication between the catch-actuating means and the atmosphere. The ends of the rail 36 are preferably inclined, as shown, so that the rise and fall of the shoe 34 will not be too abrupt.

The construction of the motorman's valve is clearly illustrated in Figs. 3 to 5. The valve-casing V may be of any suitable form, having a valve-seat 48, within which are arranged ports 49, 50, and 51, connected, respectively, to the pipe 1 leading from the reservoir, pipe 2 leading to the collector-shoe mechanism, and to the atmosphere. The movable member of the main valve may consist of disk 52, having connected ports 53 and 54 so arranged that when the operating-handle m occupies the position shown in full lines in Fig. 4 the ports 53 and 54 serve to connect together the ports 49 and 50—namely, to connect the operating mechanism for the current-collecting device to the reservoir. When the handle occupies the position shown in dotted lines in Fig. 4, the ports 53 and 54 connect ports 50 and 51 together—namely, connect the collector-shoe operating mechanism to atmosphere. The first of these positions is the working position and the second the off position of the valve. The disk valve 52 may be operated in any suitable manner—as for instance, by means of a spindle 55, connected to the disk by means of tongue 56 and groove 57, the spindle being in turn connected directly to the handle m. A spring 58, arranged between spindle and

valve, serves to force the valve firmly to its seat, while the valve is maintained centered by means of a centering-pin 59, extending from the valve into a seat 60 in the casing. The handle *m* is provided with an elongated downwardly-projecting sleeve 61, within which is arranged a coiled spring 62, having its opposite ends secured, respectively, to the sleeve and to the valve-casing, as at 63 and 64. This spring is so arranged that when the valve is turned to its working position the spring is put under tension in order that when otherwise free the handle is brought to its off position. A reciprocating catch 65 is mounted in the plane which the handle occupies when in its "on" position and when in its operative position engages with a lug 66 on the handle. The catch 65 consists of a head 67, preferably beveled 20 on one side and affording on the other side a square shoulder for receiving the lug 66, said head being formed upon or secured to the upper end of the stem 68. The stem 68, which may be held against rotation by means 25 of a pin 73, operating in ways 74, projects downwardly into a chamber 69 and carries at its lower end a piston 70, which fits the chamber 69 snugly. A small passage 71 leads from the chamber 69 at a point beneath the piston 70 to the passage 72, leading from the port 50 to the pipe 2, and a larger passage 75 beneath the piston 70 connects the chamber 69 to the pipe 3. It is evident that by reason of the passage 71 the ultimate condition 30 within the chamber 69 will be the same as that within the cylinder 30 of the collector-shoe mechanism—namely, when the main valve is turned to its off position any pressure which may exist within the chamber 69 will be dissipated through the passage 71, passage 72, ports 50, 53, 54, and 51 to atmosphere, while, on the other hand, when the main valve is moved to its on position, supplying air to the collector-shoe mechanism, 35 air will also pass into the chamber 69 and will raise the pressure therein and in the pipe 3. Consequently when the main valve is turned to its on position compressed air is supplied to the chamber 69 at a point beneath the piston 70, and the piston will be forced upwardly until head 67 engages with the lug 66 on the handle *m*. The valve is thus maintained in its on or working position against the tension of the spring until the catch 65 is again retracted.

When the car or locomotive approaches the point at which the collector-shoe is to be retracted, the air in pipe 3 is exhausted in a manner heretofore described, and consequently the air will likewise be exhausted from beneath the piston 70. The piston will therefore drop through gravity, assisted, if desired, by means of the spring 76, releasing the handle *m* and permitting the 65 spring 62 to throw the valve to its off position.

Exhausting the air in pipe 3 does not exhaust the air from the trolley mechanism by reason of the smallness of the passage 71; but the exhausting of the air from the trolley mechanism is quickly accomplished 70 by means of the main valve as soon as it reaches its off position.

In case it is desired to return the motorman's valve to its inoperative position without first exhausting the air from the pipe 3 75 the catch 65 may be depressed by means of a pin 77, slidably arranged in the handle *m*, adjacent the lug 66. A lever 78, pivoted to the handle at 79, engages with the upper end of the pin 77 and by depressing the end of the 80 lever the pin is forced downwardly, carrying the catch with it until the lug 66 is free therefrom, whereupon the handle may immediately resume its off position.

Although I have described in detail only 85 one form of the present invention, I do not desire to limit the present invention to the particular form illustrated, since in its broader aspects the present invention may be embodied in various forms.

What I claim as new, and desire to secure by Letters Patent of the United States, is—

1. In current-collecting apparatus for electric railways, a current-collecting device, controlling means therefor including a manually-controlled member, and means controlled by the engagement of a device carried by the car and a device located adjacent the roadway for causing said manually-controlled member to assume a definite position. 90

2. In a current-collecting apparatus for electric railways, a current-collecting device, means controlled by a member under the control of the operator for retracting said current-collecting device, and means controlled by 105 the engagement of a device carried by the car and a device arranged adjacent the roadway for controlling the said member.

3. In current-collecting apparatus for electric railways, a current-collecting device, means controlled by a manually-controlled member for retracting said current-collecting device, automatic actuating means for the said member, and means controlled by the engagement of a device carried by the car 110 and a device arranged adjacent the roadway 115 for controlling said automatic actuating means.

4. In current-collecting apparatus for electric railways, a current-collecting device, a motorman's valve, means controlled by the motorman's valve for operating said current-collecting device, automatic actuating means for said motorman's valve, and means controlled from a point adjacent the roadway 120 125 for controlling said automatic actuating means.

5. In current-collecting apparatus for electric railways, a current-collecting device, means including a motorman's valve for re- 130

tracting said current-collecting device, automatic actuating means for moving said valve to the retracting position, and means controlled from a point adjacent the roadway for controlling said automatic actuating means.

6. In current-collecting apparatus for electric railways, a current - collecting device, pneumatically-actuated means for controlling said current-collecting device, a motorman's valve for connecting said pneumatically-actuated means to a source of supply of compressed air or to exhaust the same, means for causing said valve to move automatically to the exhaust position, and means controlled from a point adjacent the roadway for controlling the automatic operation of the valve.

7. In current-collecting apparatus for electric railways, a current - collecting device, pneumatically-actuated means for controlling said current-collecting device, a valve controlled by the motorman and having "on" and "off" positions, means for causing said valve to move automatically from the "on" position to the "off" position, and means controlled from a point adjacent the roadway for controlling the automatic movement of the valve.

8. In current-collecting apparatus for electric railways, a current - collecting device, pneumatically-actuated means for controlling said current-collecting device, a valve controlled by the motorman and having "on" and "off" positions, the arrangement being such that the valve normally tends to assume its "off" position, means for locking said valve in its "on" position, lock-releasing means, and means controlled from a point adjacent the roadway for controlling said lock-releasing means.

9. In current-collecting apparatus for electric railways, a current - collecting device, pneumatically-actuated means for controlling the same, a main valve adapted when in one position to connect said pneumatically-actuated means to a source of supply of compressed air and when in another position to exhaust the same, the arrangement being such that the valve tends normally to return to the exhaust position, a catch for holding said valve out of its exhaust position, means including a valve for controlling said catch, and means arranged adjacent the roadway for operating said latter valve.

55 10. In a valve mechanism, a main valve, a pneumatically-actuated catch for said valve, and means for admitting compressed air to the catch-actuating means when the main valve is moved to a certain position.

60 11. In a valve mechanism, a main valve tending normally to assume its inoperative position, a catch for holding said valve in an operative position, pneumatically-actuated operating means for said catch arranged to move said catch into locking position only

when compressed air is being supplied to the main valve.

12. In a valve mechanism, a main valve, a spring arranged to hold the valve in its inoperative position, a catch for holding said valve in an operative position against the tension of the spring, pneumatically-actuated operating means for said catch arranged to move said catch into locking position only when the main valve is being supplied with compressed air.

13. In a valve mechanism having an inlet-port, an outlet-port and an exhaust-port, a movable member controlling said ports, a lock for said movable member, and pneumatic controlling means for said lock in open communication with said outlet-port.

14. In a valve mechanism having an inlet-port, an outlet-port and an exhaust-port, a movable member arranged to connect said outlet-port to said inlet-port or to said exhaust-port, a lock for said movable member, and pneumatic controlling means for said lock in open communication with said outlet-port.

15. In a valve mechanism having inlet, outlet and exhaust ports, a movable member for connecting said outlet-port to said inlet-port or to said exhaust-port, the arrangement being such that the movable member tends to assume the position in which it connects the outlet-port to the exhaust-port, a catch for locking the said member in position for connecting said outlet-port to said inlet-port, and pneumatically - actuated controlling means for said catch in open communication with said outlet-port.

16. In a valve mechanism having inlet, outlet and exhaust ports, a movable member for connecting said outlet-port to said inlet-port or to said exhaust-port, the arrangement being such that the movable member tends to assume the position in which it connects the outlet-port to the exhaust-port, a catch for locking the said member in position to said inlet-port, pneumatically-actuated controlling means for said catch in open communication with said outlet-port, and means for manually operating said catch.

17. In a valve mechanism having inlet, outlet and exhaust ports, a movable member for controlling said ports and arranged to have a tendency to return to its inoperative position, a manually-retracted catch adapted to lock said movable member in its operative position, and pneumatically-actuated means for moving said catch into locking position operatively connected to said outlet-port.

18. In current-collecting apparatus for electric railways, a current-collecting device, pneumatically - actuated controlling means therefor, a motorman's valve normally connecting said controlling means to atmosphere and arranged in its operative position to con-

nect said controlling means to a source of compressed-fluid supply, a spring tending to hold said valve in its normal position, a catch for locking said valve in its operative position, pneumatic controlling means for said catch including a valve, and a stop adjacent the roadway for operating said latter valve.

In witness whereof I have hereunto set my hand this 9th day of March, 1905.

FRANK E. CASE.
